UNITED STATES PATENT OFFICE

SVERRE NORD AND ABRAHAM ANDERSON, OF SEKIU, WASHINGTON

LOADING-BOOM.

1,313,108.

Specification of Letters Patent.

Patented Aug. 12, 1919.

Application filed January 31, 1919. Serial No. 274,282.

To all whom it may concern:

Be it known that we, SVERRE NORD and ABRAHAM ANDERSON, citizens of the United States, residing at Sekiu, in the county of Clallam, State of Washington, have invented a new and useful Loading-Boom, of which the following is a specification.

This invention relates to booms for use in loading logs, the principal object being to provide a loading boom which can be used with hooks and tongs whereas heretofore it has been necessary to employ tongs only.

With the foregoing and other objects in view, which will appear as the description proceeds the invention consists of certain novel details of construction and combination of parts which will be hereinafter more fully described and pointed out in the 20 claims it being understood that various changes may be made in the construction and arrangement of the parts without departing from the spirit or sacrificing any of the advantages of the invention as set forth in the 25 appended claims.

In the accompanying drawing the preferred form of the invention has been shown, in said drawing.

Figure 1 is a diagrammatic view of the 30 boom and the apparatus with which it is used.

Fig. 2 is a plan view of the said apparatus.

Fig. 3 is an enlarged plan view of the 35 boom.

Referring to the figures by characters of reference 1 designates an arcuate strap or yoke, provided in its ends with eye bolts 2. To the yoke are secured opposed angle 40 brackets 3, between which are fitted the ends of diverging beams 4, which are bolted together and to the brackets 3, as indicated at 45. At a suitable point between the ends of the beam a spacing block 6 is located, this 50 block being held in place in any manner desired, as by means of tie bolts 7. Interposed between the beams adjacent those ends thereof remote from the yoke are connecting bars 8, arranged in pairs and provided with terminal ears 9, bolted to the beams. The bars of each pair are connected by a strap 10, and each bar has longitudinal series of apertures 11, whereby the strap 10, can be connected adjustably to the bars. The bars of each 55 pair are adjustably engaged by links 12, ex-

tending from the ends of sheave blocks 13, which can be adjusted to any position desired between the bars of each pair by detaching the links 12 from the bars 8, sliding them along the bars, and then refastening the links to the bars, the series of openings in the bars 8 being adapted to receive the bolts or the like used for fastening the links. Tie rods 14, can be located wherever desired in order to hold the bars 4 against spreading.

In using the boom herein described the yoke 1 is placed astride a mast 15 which can be a tree trunk properly dressed. A bolt 16 is extended through the boom close to 70 the yoke and is engaged by a supporting cable 17 tied to the mast. A chain 18 is attached to eye bolts 2 and is extended around the mast 15 as shown so as to hold the yoke 1 against the mast.

Guy lines 19 are extended from the upper portion of the mast and secured to stumps F, or the like.

The outer end of the boom is supported by cables 20 fastened to the mast and mounted to travel on the outer cable 20 is a carriage 21 to which is connected a sheave block 22. A cable 23 engages and supports the block 22 and one end attached to a ring 24 supported on one of the guys 19 and held by a line 25. A crotch line 26 is connected to the block 22 and has its lower ends movably engaging the blocks 13 and provided with grapples or tongs 27 or with hooks 28. These tongs and hooks are adapted to engage a log L for the purpose of lowering it onto or lifting it from a car C mounted on a track T adjacent to the mast 15.

Sheave blocks 29 are connected to the mast 15 and also to one of the guys 19 and are engaged by a haul back line 30 secured at one end to the outer ends of the boom 12 and at its other end to a drum 31 of the operating engine 32. The cable 23 is extended over a sheave 33 connected to the 100 mast and is then extended downwardly to another drum 34 driven by the engine. In using the apparatus the cable 23 is paid out so as to lower the crotch line 26 and thus correspondingly lower the grapples and hooks which are then placed in engagement with the log to be handled. The cable 23 is then taken up so as to cause the crotch line 26 to pull on the grapples and hooks and grip and lift the engaged log. After 110

the log has thus been elevated the cable 30 is wound on its drum 31 and the beams 4, with the load, caused to swing laterally about the mast 15.

5 It will be seen that by providing mechanism such as described the boom can be operated readily and by the use of this boom either tongs or hooks can be used for loading logs onto a car.

10 What is claimed is:

1. The combination with a mast, of a boom mounted to swing therearound, a supporting cable connected to the mast and to the boom, a carriage mounted to travel on said cable, a sheave block connected to the carriage, a cable anchored at one end and extending through the sheave block, guides for said cable, means for taking up and paying out said cable, a crotch line connected 15 to said block and extending through the boom, guides in the boom for said line, and log engaging elements carried by the crotch line.

2. The combination with a mast, of a boom including beams diverging from one end, said beams being connected together at 20 line.

25 said end, a yoke attached to the beam at said ends and straddling the mast, means connected to the ends of the yoke and extending around the mast for holding the boom to the mast, means for supporting the boom from the mast, said means including a cable secured to the mast and boom, connecting bars arranged in pairs and secured to and between the beams, sheave blocks adjustably mounted between the bars of each pair, cables connecting the outer end of the boom to the mast for supporting said end, a crotch line extending past the sheaves of the boom and provided with log engaging 30 elements, and means movably engaging the crotch line for raising and lowering it relative to the boom.

35 In testimony that we claim the foregoing as our own, we have hereto affixed our signatures in the presence of two witnesses.

SVERRE NORD.
ABRAHAM ANDERSON.
